Patented May 24, 1927.

UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVETING MACHINE.

Application filed November 8, 1926. Serial No. 146,934.

This invention relates to riveting machines, and particularly to the rivet guiding and positioning mechanism thereof.

The general objects of the invention are to provide simple and practical means for guiding and accurately positioning rivets, particularly rivets of the diamond head staple type, and for holding them under control during the driving stroke of the machine. These objects, as will appear hereinafter, are accomplished by providing the so-called "pocket", in which individual rivets are segregated and held for the driving operation with structural features and conformations which constitute the present invention.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claim.

In the accompanying drawings, which are to be taken as a part of this specification, and in which I have shown merely a preferred form of embodiment of my invention,

Figure 1 is an elevation showing parts of the rivet feeding, holding and driving mechanism of a riveting machine;

Figure 2 is an elevation of the pocket;

Figure 3 is a section, with parts broken away and parts in elevation;

Figure 4 is a section taken on the line 4-4 of Figure 3;

Figure 5 is a section taken on the line 5-5 of Figure 3; and

Figure 6 illustrates a type of rivet for which my device is adapted.

Referring to the numerals on the drawings there is shown at 7 a portion of the head of a riveting machine, in which operates a driving plunger 8. Rivets or staples 9 are fed by gravity down inclined chute 10, from which they are released one at a time by a feed slide in the usual manner. The rivet holding, guiding and controlling members are located below and at the end of the feed chute, beneath the plunger, and consists of a so-called "pocket", comprising a pair of cooperating members 11 and 12, carried at the lower ends of spring arms 13 and 14, shown as seated in recesses 15 in the opposite

sides of a portion of the head, and as held therein by a bolt 16 which, for purposes of ready removability, is shown equipped with a thumb-screw 17. This construction enables the pocket members to yield during the passage of the rivet therethrough and to firmly hold the rivet during such passage. The pocket members have meeting flat surfaces 18, and each member is excavated so that when the flat surfaces are in contact, as in Figure 2, there exists a tubular passage having an enlarged part defined by shoulders 19 and of a size such that it will receive the head of the rivet or staple; while below the head-receiving portion or seat 19 a vertical passage extends, of size in cross-section very slightly smaller than the size of the staple head, and conforming generally to the shape of such head. The opposed faces of members 11 and 12 are cut so there are provided ends walls against which the legs of the staple bear after the staple has been driven from the seat 19 down into the passage (see Figure 5), and side walls 20 (see Figure 5) against which portions of the edge of the staple head bear. And beginning at a point somewhat below seat 19 opposed faces of the members 11 and 12 are grooved, as indicated at 21, the grooves being so located and of such depth that the projecting side points or edges of the staple head will not touch the bottoms of the grooves as the staple descends through the passage. These grooves 21 run all the way to the lower ends of members 11 and 12, and at their upper ends gradually decrease in depth as they approach the short vertical surfaces 22 which separate them from the seats 19. The edges of the pocket members adjacent the end of the feed chute 10 are cut away from the top and part way towards the lower ends thereof, providing an opening flaring outwardly towards the feed chute and through which the legs of the staple pass as the staple moves from the feed chute to the position shown in Figure 4, where the head rests on seat 19.

Operation.

As the lowermost staple in the feed chute is released by the feed slide it drops down into position beneath the plunger, the head of the rivet seating itself on the ledge 19 and the legs passing through the flaring opening of the pocket (Fig. 4).

As the plunger descends it engages the

head of the staple and forces the staple downwardly, thereby forcing apart the spring-pressed pocket members. In case there are any burrs or unevennesses on the side points or edges of the rivet head, the grooves 21 will permit them to pass, so that the passage of the rivet may be under better control and not subject to interference by way of unequal friction on opposite sides of the rivet head, tipping, &c.

I claim:—

A pocket of the kind described comprising matching spring-pressed members formed

to define between them a rivet-passage oblong in cross-section having a surrounding 15 rivet-head ledge at its upper end and an outwardly flaring opening into the side of the passage, the passage providing end-walls for contact with the ends of an oblong rivet-head and side-walls for contact with the side-walls of the rivet head, said side-walls, below the ledge being grooved all the way to the lower end of the passage.

In testimony whereof I affix my signature.

EDWIN B. STIMPSON.
